LOCOMOTIVE SUPERHEATER

William Shane, Paterson, N. J., assignor to The
Superheater Company, New York, N. Y.

Application June 26, 1937, Serial No. 150,454

1 Claim. (Cl. 122—462)

The invention relates to locomotive superheaters of the type in which a header located in the smoke box has the ends of tubular elements secured to its lower side, which elements extend into the flues of the locomotive. The gases issuing from the flues carry cinders with them, and where they impinge against the element ends and the means used to secure these ends to the header the result is rapid cutting of these parts. The object of the present invention is to provide a protection of parts involved against such cutting.

The invention is illustrated in the accompanying drawings in which Fig. 1 is a vertical longitudinal section of a portion of the smoke box and the adjacent boiler parts of a locomotive showing the superheater header and parts of the superheater elements as well as my protective device in place. Fig. 2 is a section on line 2—2 of Fig. 1. Fig. 3 is a detail view of a frame enclosing an opening in the smoke box wall required in connection with my protective device, and Fig. 4 is a sectional view on line 4—4 of Fig. 3, the protective plate being shown partially withdrawn.

The boiler shell appears at 1 and the smoke box sheet at 2. The front flue sheet 3 has the front ends of flues 4—4 expanded into it and in these flues are located the superheater elements 5—5. The ends of these elements are secured to the bottom of the superheater header 6. This is done by means of bolts 7 which engage clamps 8 and pull them upward against washers 9—9 interposed between the enlarged heads 10—10 and the clamps. By pulling up the nuts on the bolt 7 the enlarged heads 10—10 are forced into engagement with seats on the under side of the header. This construction is standard and well known.

In installations of this type the header 6 is in such a position in the smoke box that gases issuing from the upper row of flues 4 impinge against the element ends and the means used to secure these ends to the header. These gases carry cinders from the fire box with them and the cinders, striking the parts in front of the flues, wear them away rapidly.

My invention consists in providing a shield 11 protecting the superheater element ends and adjacent parts against the impingement of the

gases and cinders. This plate 11 extends across the smoke box from side to side, its ends resting in slotted brackets 12, which are welded or otherwise secured to the smoke box wall. The smoke box wall itself is provided with a slot 13 opposite one end of the shield 11. The slot 13 is surrounded by a frame 15 which is welded or otherwise secured to the smoke box sheet 2 and forms a seat for a cover plate 16 secured in place, as by the cap-screws 17. To facilitate the removal of the shield 11 I preferably provide a ring 18 extending through an opening in the end of the shield 11. This ring is swung out of the way as in Fig. 2 when cover 16 is put in place. When required for removal of the plate 15 it is tipped out of this position as shown in Fig. 4 and serves as a convenient means of pulling the shield out.

It will be noted that the location of the header relatively to the topmost flues and superheater elements located in such flues is such that these topmost elements cannot be removed without taking out the shield 11. It is for this purpose that the provision for easy removal is made. My invention comprises not only the provisions of a shield but the provision also of easy means of taking it out of the way when required for the removal of superheater elements.

What I claim is:

In a locomotive equipped with a superheater of the type in which tubular elements extend into the flues and have their ends secured to a header located in the smoke box above the outlets of the flues in a position such that cinders carried by gases issuing from the flues travel in a direction toward the ends of the elements and the means securing them to the header; a shield placed adjacent to the bottom of the header and between the element ends and the flues so as to prevent impingement of cinders against the element ends and the means whereby they are secured to the header, the shield comprising a narrow vertical plate; slotted supports secured to the smoke box walls to receive the ends of the shield, the smoke box wall being slotted opposite one end of the shield whereby the shield can be readily withdrawn; and a cover to close said smoke box wall slot.

WILLIAM SHANE. 50
